APPARATUS FOR THE MANUFACTURE OF
PLASTIC EXPLOSIVE PELLETS

Edgar G. Guenther and Robert C. Burton, Kingsport, Tenn., assignors, by mesne assignments, to the United States of America as represented by the Secretary of War

Application July 16, 1943, Serial No. 495,084

1 Claim. (Cl. 18—4)

1

The present invention relates generally to thermoplastic explosive compositions, and more particularly to an improved apparatus for casting and pelletizing the same.

Heretofore it has been common practice in manufacturing high explosives to produce a flaked, grained, crystalline or other free-flowing material which can be safely charged into agitated mixing vessels having clearances of less than 1 inch. When pellets of single explosives or mixtures, such as TNT or Amatol, are required for pellet loading, the usual practice is to pour the molten explosive into pans about 1 inch deep. After the resulting slabs have cooled, they are broken into pieces of the desired size, using mallets or similar means. This procedure of casting slabs has also been used for the preparation of explosive mixtures for shipment when one of the ingredients is too dangerous to ship alone. It is necessary to remelt a major part of these slabs at loading plants, which is both dangerous and time consuming.

The object of the present invention is to provide apparatus for manufacturing high explosive pellets of a size and shape which can be remelted quickly and safely, and which can be used directly for pellet loading.

Another object is the provision of apparatus for producing free-flowing pellets from thermoplastic explosive compositions.

Other objects and advantages will be apparent as the invention is hereinafter more particularly described.

A preferred illustrative embodiment of the present invention is shown in the appended drawing, wherein:

Figure 1 is a side elevation of the pelletizing apparatus as a whole;

Figure 2 is a section on the line 2—2 of Figure 1;

Figure 3 is a plan of the extrusion vessel, the direction of belt movement and the pellet rows being indicated by the arrow and the dotted lines, respectively;

Figure 4 is a vertical cross section of the extrusion vessel shown in Figure 3;

Figure 5 is a perspective view of an agitator for the extrusion vessel;

Figure 6 is a perspective view of the scraper and apron at the discharge end of the apparatus shown in Figure 1; and

Figure 7 is a perspective view of one of the formed pellets.

Referring particularly to Figure 1, the apparatus comprises a machine bed or frame 1 supporting at each end, a rotatably mounted pulley

2

wheel 2 and 3, one of which (2) is driven in any suitable manner, for example by means of a belt 2a passing over pulley 2b. The two wheels 2 and 3 carry an endless metallic belt 4 preferably made of stainless steel. Suitable supporting skids 5, preferably of wood, on the underside of the advancing belt prevent the belt from vibrating and thereby obviate the formation of disc-shaped pellets. The under side of the returning belt is supported by idle rollers 6, and a swinging belt tightener roller 6a may be provided on the upper side of the returning belt.

At the feed end of the belt, a steam jacketed extrusion kettle 7 is supported a suitable distance 15 above the belt 4, on a kettle bracket 8. The distance of the kettle 7 above the belt 4 is so adjusted that uniform droplets of explosive will form during the period of fall from the kettle to the belt.

20 The details of the kettle are more particularly shown in Figures 3, 4 and 5. The kettle consists of two concentric nested pots 20 and 21 suitably united to form a single jacketed vessel. Suitable outlet and inlet ports 22 and 23 permit steam to be introduced into the annular space between the pots 20 and 21. The bottom of the pot is provided with a number of extrusion holes, 24, uniformly spaced and arranged in the form of a circle which are also steam jacketed, as shown, the holes being 30 so located as to provide a uniformly spaced feed. A twisted-anchor agitator 25 provided with upturned ends 26 is connected to a hub 27 which has a socket connection with drive shaft 28, so that the pot contents may be stirred during operation. Set screw 29 secures hub 27 to drive shaft 28. Shaft 28 is rotatably supported in the upright 12 (Fig. 1) and adapted to be rotated by the pulley wheel 11 connected through a V-belt (not shown) to a suitable source of power (not shown) 35 for slowly rotating the agitator shaft 28.

Above and below the advancing belt 4 are disposed suitable air ducts 12 and 13 provided with spaced air outlet slots 30 on the face adjacent to the advancing belt, so that cool air may be blown 45 against the upper and lower surface thereof. The ducts 12 and 13 are connected through conduits 14 and 15 to air trunk 31 which is connected with a suitable pressure fan (not shown).

At the discharge end of the belt, a wooden 50 scraper blade 17 is provided to remove any explosive pellets which adhere to the belt 4. The explosive pellets fall into a suitable hopper 16, being collected on the apron 18 which desirably consists of a frame covered with cloth 32 to cushion the fall.

In operation, the plastic explosive is placed in the steam jacketed extrusion vessel 7 wherein a constant level is desirably maintained in order to obtain drops of uniform volume. As the agitator 25 revolves, the plastic flows through the extrusion holes 24 and falls in the form of discrete globules 9 through the air onto the advancing belt 4. As the deposited droplets, supported on the belt, are carried forward between the upper and lower air ducts 12 and 13, they are gradually solidified. When the pellets reach the discharge end most of them slide onto the apron 18 or directly into the hopper 16. Any pellets which adhere to the belt are removed by the scraper blade 17 and thence fall into the hopper 16.

By suitable adjustment of the plasticity of the explosive, the size of the extrusion holes 24, the depth of the plastic in the extrusion vessel 7, the height of the fall from the extrusion vessel 7 to the belt 4, the cooling rate, the length of the belt etc., the explosive may be obtained in pellets of varying size and shape. Generally the pellets, in configuration, resemble an unopened rose bud, as shown in Figure 7, and are free-flowing.

As an example of the preparation of an explosive composition that may be formed into pellets according to the present invention, the following is given:

One hundred parts by weight of water is placed in a steam-jacketed mixing vessel provided with an efficient stirrer and equipped with a hood for removing TNT fumes. 400 parts by weight of TNT is then added and the mixture agitated until the TNT is completely melted (15 pounds of steam pressure being applied in the jacket). After allowing the mixture to come to rest, the water separates and rises to the top of the molten TNT. About 705 to 750 parts by weight of moist cyclonite (15-20% moisture, corresponding to 600 parts of cyclonite on a dry basis) is then added slowly through the water layer which appears to disperse the cyclonite and permit rapid mixing with the TNT. After the cyclonite is all added, the mixture is stirred for about one-half hour and the water layer then decanted. Heating is continued for about one and one-half hours in order to vaporize all the water from the molten mass. During the foregoing operations, 15 pounds steam pressure is maintained in the jacket until the temperature of the molten composition reaches about 104° C. Thereafter, the steam pressure in the jacket is reduced to about 5 pounds. By holding the molten composition about 104° C., it was found that the subsequent operation of wax incorporation is facilitated.

After the water is substantially completely removed from the TNT-cyclonite composition, 1% of a previously melted amorphous petroleum wax, for example "Aristowax" sold by Union Oil Co. of California, is mixed with the TNT-cyclonite mixture in the mixing vessel, while maintaining a mixture temperature of 104° C.

Preferably an agent for lowering the interfacial tension between the cyclonite and the amorphous wax is added to the amorphous wax before it is added to the TNT-cyclonite mixture. For this purpose a large number of long chain hydrocarbon derivatives containing polar groups (e. g., carbonyl, carboxyl, hydroxyl, etc.) may be used.

The long chain fatty acids such as stearic acid, for example, are illustrative of the type of interfacial adjuncts which are suitable. It is preferred, however, for economical and other reasons, to employ the crude mixture of polar compounds obtained by bubbling air through heated petroleum hydrocarbons (e. g., those derived from Pennsylvania crudes) in the presence of oxidation catalysts such as manganese oleate. The resulting water insoluble, oil-soluble, oxygen-containing petroleum derivatives consist of alcohol, ketone and carboxyl compounds as well as esters and probably some lactones, etc. These complex mixtures are available on the market under the trade name "Alox," such as "Alox-310," "Alox-350" and "Alox-600." Alox-600 to the extent of about 10% by weight of the amount of the amorphous petroleum wax used is added to said wax before it is added, as above described, to the TNT-cyclonite mixture.

The proportion of cyclonite in the above described explosive composition may be varied, as will be understood by the person skilled in the art, and indeed, in some instances it may be desirable to increase the proportion of cyclonite to 62-63% by weight of the composition, in order to obtain a more workable composition.

The cyclonite referred to above is an explosive which has a molecular formula of $C_3H_6O_6N_6$, and a melting point in the pure state of approximately 205° C. It is considered to be cyclotrimethylenetrinitramine, and may be prepared by the method described by Hale in the Journal of the American Chemical Society, vol. 47, page 2754, issued in 1925.

In the foregoing detailed description, it will be apparent that many variations may be made without departing from the spirit and scope of the invention. We therefore intend to be limited only in accordance with the following patent claim.

We claim:

An apparatus for the manufacture of uniformly sized and shaped high explosive pellets comprising an extrusion chamber having its sides and bottom surrounded by steam jacketing forming therewith a steam space having inlet and outlet connections thereto, bottom openings in said chamber connected by pipe portions leading through said steam space and said jacket, a rotatably mounted S-shaped anchor agitator having upturned ends, said agitator cooperating with said pipe portions to move a plastic explosive composition therethrough, a flexible conveyor mounted beneath said chamber for receiving and moving said extruded material, supporting means for dampening the vibration of said conveyor while in motion, and means for cooling said extruded material on said conveyor.
